US0D1061586S

(12) **United States Design Patent** (10) Patent No.: **US D1,061,586 S**
 Matsuda et al. (45) Date of Patent: ** Feb. 11, 2025

(54) **DISPLAY PANEL OR SCREEN OR PORTION THEREOF WITH GRAPHICAL USER INTERFACE**

(71) Applicant: **SONY GROUP CORPORATION**, Tokyo (JP)

(72) Inventors: **Hazime Matsuda**, Kanagawa (JP); **Matthew Forrest**, Kanagawa (JP); **Keiichi Yoshioka**, Tokyo (JP)

(73) Assignee: **SONY GROUP CORPORATION**, Tokyo (JP)

(**) Term: **15 Years**

(21) Appl. No.: **29/808,213**

(22) Filed: **Sep. 17, 2021**

(51) LOC (15) Cl. **14-04**

(52) U.S. Cl.

USPC **D14/486**

Primary Examiner — Rachel A. Voorhies

(74) Attorney, Agent, or Firm — Michael Best and Friedrich LLP

(57) **CLAIM**

The ornamental design for a display panel or screen or portion thereof with a graphical user interface as shown and described.

DESCRIPTION

FIGURE is a front view of a display panel or screen or a portion thereof with a graphical user interface showing our new design.

The outermost broken lines illustrating unclaimed portions of a display panel or screen or a portion thereof with a graphical user interface form no part of the claimed design. The broken lines within the outermost broken lines illustrating a graphical user interface form no part of the claimed design. The dot-dash broken lines illustrating boundaries of the claimed design form no part of the claimed design.

1 Claim, 1 Drawing Sheet
